Primary Examiner — Robin V Webster*(74) Attorney, Agent, or Firm* — Todd J. Langford(57) **CLAIM**

The ornamental design for a portable spray system, as shown and described.

DESCRIPTION

FIG. 1 is a perspective view of the portable spray system;

FIG. 2 is a front side view;

FIG. 3 is a back view;

FIG. 4 is a left side view;

FIG. 5 is a right side view;

FIG. 6 is a top view; and,

FIG. 7 is a bottom view thereof.

The broken lines showing the bottom of the portable spray system are for the purpose of illustration only and form no part of the claimed design.
